UNITED STATES PATENT OFFICE.

STANLEY P. ROCKWELL, OF WEST HARTFORD, CONNECTICUT.

DILATOMETER.

Application filed June 29, 1928. Serial No. 289,188.

My invention relates to the class of devices more particularly employed for determining certain phenomena in metals when subjected to variations in temperature, and an object 5 of my invention, among others, is the production of a device by means of which extreme accuracy may be secured in determining certain results.

One form of device embodying my invention and in the construction and use of which the objects herein set out, as well as others, may be attained, is illustrated in the accompanying drawings, in which—

Figure 1 is a view in elevation of an apparatus embodying my invention with the furnace broken away to show the interior thereof.

Figure 2 is a similar view, but looking at the apparatus from a point located at right angles to the point of view of Figure 1, and with parts beyond omitted.

Figure 3 is a top view of the device.

Figure 4 is a view in section of a portion of the device on a plane denoted by the 25 dotted line 4—4 of Figure 1.

In the accompanying drawings the numeral 5 denotes as a whole an instrument by means of which certain results may be obtained in the heat treatment of metals, such 30 instrument being of old and well known construction and forming, except in connection with parts to be hereinafter described, no part of my present invention and being illustrated herein merely for a disclosure of 35 such invention. Said instrument is shown as supported upon a table 6 and comprises a lever 7 that, when moved, actuates an indicator 8 and a recording mechanism 9, the latter including a cylinder 10 on which a 40 sheet of paper is placed to receive the record.

My improved device comprises a furnace 11 which may be, as to general characteristics, of any well known form and construction, that herein shown being of the electric 45 type and which is employed for the purpose of heating pieces of metal to determine certain characteristics thereof.

It is of value in many instances to determine to as exact a degree as may be possible 50 the amount of contraction and expansion of metals under heating and cooling conditions, but with apparatus heretofore used extreme accuracy has been impossible by reason of the influence of outside agencies upon the 55 metal. For instance, with a recording instrument, as herein shown and heretofore

used, a piece of metal 12 has been placed in the furnace 11, resting upon a support placed on the bottom to the furnace, and a connection has been made between said piece 60 of metal and the lever 7 of the recording instrument. The amount of expansion and contraction of the piece of metal, however, in this operation, has been influenced to a great extent by the furnace as well as the 65 supports thereof, and also by the support for the metallic article within the furnace, the expansion and contraction of all of which must of necessity be considered and which cannot accurately be separated from the ex- 70 pansion and contraction of the metal piece itself owing to the great degree of influence exerted by such members. In order to reduce these outside influences to a minimum I provide a base 13 to support the piece of 75 metal 12, this base resting as upon a base plate 14 of the instrument as a whole. A rod 15 is secured to and rises from the base 13 and forms the immediate support upon which the piece 12 rests. This rod is con- 80 structed of quartz or other suitable material that is influenced as to expansion and contraction to a minimum degree by the furnace. Resting upon the piece 12 of metal 85 is another rod 16 that is in contact with the piece of metal which is also composed of quartz or other similar material not readily influenced by the heat. Upon the rod 16 is a head 17 secured to the lower end of a rod 18, the upper end of which is in contact with 90 the lever 7, said rod 18 being loosely attached to the frame of the instrument 5 as by means of screws 19 projecting through holes in the frame considerably larger in diameter than the screws so that in the operation of the instrument upon any piece of metal within its range the screws 19 will not touch the edges of the holes through which they project. With different sizes of pieces 95 12 being operated upon an adjusting screw 100 20 is employed to adjust the position of the frame of the instrument to set the pointer of the indicator 8 at zero.

In order that the heat of the furnace shall affect the rods 15 and 16 to a minimum degree the furnace is provided with openings 105 21 at the top and bottom considerably larger in diameter than that of said rods so that there is quite a little space between the edges of the openings and the outer surface of the 110 rods.

In the use of the apparatus thus described

it will be noted that practically the entire expansion or contraction of the metal piece 12 will be indicated by the recording and indicating instrument, the influence of the 5 heat of the furnace upon the supports for the metal piece being practically negligible, and even this being reduced by employing a material which is little influenced by the 10 heat of the furnace. If it shall be desired to obtain more accurate data than are indicated by the instrument, the quartz rods may be placed in contact, the furnace heated to the required degree and the reading of the 15 recording instruments taken. Then, after a piece of metal has been heated to the required degree and a reading taken to denote the amount of expansion, the amount of expansion before taken when the quartz rods only were in the furnace may be deducted 20 and this will enable an extremely close determination of the expansion of contraction to be had. In fact, in most instances it will not be necessary to take into consideration the difference in expansion last described. 25 In accordance with the provisions of the patent statutes I have described the principles of operation of my invention, together with the apparatus which I now consider to represent the best embodiment thereof; 30 but I desire to have it understood that the device shown is only illustrative and that the invention may be carried out by other means and applied to uses other than those above set out.

35 I claim—

1. A dilatometer including a heating furnace, a support projecting from outside of the furnace to a point therein without touching the furnace and adapted to receive within the furnace a piece to be tested, an indicating instrument, a connecting element adapted to rest upon said piece and to extend to a point outside the furnace without touching the same, and a connec- 40 45 50 55 60 65 70 75 80 85 90

tion between said connecting element and said indicating instrument for actuation of the latter.

2. A dilatometer including a heating furnace, having openings therein, a support smaller than said openings and projecting from outside the furnace to a point therein and adapted to receive a piece to be tested, an indicating device, a connecting element smaller than one of said holes and projecting therethrough to a point outside of the furnace, said element being adapted to rest upon said piece, and a connection between said element and said indicating piece for actuation of the latter.

3. A dilatometer including a heating furnace, a support having minimum heat affecting qualities projecting from outside the furnace to a point therein without touching the furnace and adapted to receive within the furnace a piece to be tested, an indicating instrument, a connecting element composed of material adapted to be affected by heat to a minimum extent and adapted to rest upon said piece and to extend to a point outside the furnace without touching the same, and a connection between said connecting element and said indicating instrument for actuation of the latter.

4. A dilatometer including a heating furnace having a hole at each end thereof, a support composed of quartz projecting from outside the furnace through one of said holes, said support being smaller in diameter than said hole and being adapted to receive a piece to be tested, an indicating instrument, a connecting element composed of quartz adapted to rest upon said piece to pass through the other hole in said furnace and smaller in diameter than said hole, and a connection between said connecting element and said instrument for actuation of the latter.

STANLEY P. ROCKWELL.
